SMOKING DEVICE FILTER CARTRIDGE

Milton P. Chernack, West Hempstead, N.Y., assignor to
Delcron Products, Inc., New York, N.Y.

Filed Dec. 14, 1970, Ser. No. 26,467

Term of patent 14 years

Int. Cl. D27—01

U.S. Cl. D85—6

FIG. 1 is a perspective view of a smoking device filter cartridge showing my new design;

FIG. 2 is a bottom plan view;

FIG. 3 is a side elevational view;

FIG. 4 is a top plan view;

FIG. 5 is an elevational view showing the side opposite that seen in FIG. 3;

FIG. 6 is an end view looking from the left of FIG. 3; and

FIG. 7 is an end view looking from the right of FIG. 3.

I claim:

The ornamental design for a smoking device filter cartridge, as shown.
